UNITED STATES PATENT OFFICE.

FRANK L. O. WADSWORTH, OF SEWICKLEY, PENNSYLVANIA.

WATER-HEATER CONSTRUCTION.

1,044,954.

Specification of Letters Patent.

Patented Nov. 19, 1912.

Application filed October 3, 1911. Serial No. 652,579.

To all whom it may concern:

Be it known that I, FRANK L. O. WADSWORTH, a citizen of the United States, residing at Sewickley, in the county of Allegheny 5 and State of Pennsylvania, have invented certain new and useful Improvements in Water-Heater Construction, of which the following is a specification.

The invention relates to improvements in 10 instantaneous water heaters, and particularly to the mechanism for controlling the gas supply in such heaters.

The primary objects of the invention are; 15 the provision of a heater having both water pressure and thermostatic control of improved construction wherein any direct action of the water actuated element upon the gas valve is eliminated and such valve controlled positively by the thermostatic element to the end that the sticking of the water actuated element in any position will not interfere with the thermostatic control of the fuel supply; the provision of an improved form of controlling mechanism 25 wherein the fuel valve can be opened only when the heater is filled with water and only when the water is flowing through the heater; and the provision of a simple reliable and effective mechanism for giving the 30 control as above specified.

Certain embodiments of the invention are illustrated in the accompanying drawings, wherein:—

Figures 1 and 2 are front and side elevations respectively of an ordinary instantaneous water heater, such as that shown in the patent to Shook, No. 993,723, with my improvement applied thereto; Fig. 3 is a section on an enlarged scale through my controlling mechanism; Fig. 4 is a section through a modified form of controlling mechanism applicable to the heater as shown in Figs. 1 and 2; Fig. 5 is a section through a modified form of controlling mechanism; Fig. 6 is a detail view of a modification which may be employed in the structure of Fig. 5; Fig. 7 is a section through a modified form of controlling mechanism; Fig. 8 is a section through a modified form of controlling mechanism; and Figs. 9 and 10 are still other sections through other forms of controlling mechanisms, the controlling mechanism as shown in these figures being somewhat analogous.

Referring first to the general arrangement of the heater parts as shown in Figs. 1 and

2; A is the casing of the heater; B and C are the upper coils of the heater; D is the lower reverse coil connected to the upper coils by means of the pipe E; F are the burners 60 mounted upon the usual burner ring; G is the gas supply pipe; H is the casing of the gas valve for controlling the supply of gas to the burners; I is a pipe leading from the gas valve to the burner ring; K is the casing 65 of the water actuated member; and L is the casing of the thermostatic controlling means.

Referring now to Fig. 3 in connection with Figs. 1 and 2; 1 is the cold water inlet pipe leading from the main into the chamber 2 of the casing K; 3 is a water actuated check valve; and 4 is the outlet from the casing K leading into the pipe 5, the upper end of which is turned laterally as indicated at 5' in Figs. 1 and 2 and constitutes the 75 cold water inlet to the upper coil B. The outlet from the lower reverse coil C is through the connection 6, which connection leads into the thermostat casing 7, the upper end of such casing 7 being provided 80 with the outlet 7' leading to the service pipes of the house. The upper ends of the thermostat casing 7 and the pipe 5 are connected by means of a pipe 7", so that a circulation 85 may be secured through the coils of the heater; the connection 6, the thermostat chamber 7 the pipe 7" and the connections 5' when the outlet to the service pipes is closed, such circulation feature being common in the art as shown in the patent to Shook 90 heretofore referred to. A check valve is provided to prevent a flow to the left through the pipe 7" when the outlet 7' is opened, such check valve feature also being old in the art. The thermostat chamber 7 95 contains a thermostat of any desired construction, the one shown in the figure being of the ordinary composite type composed of an outer tube 8 of zinc, copper or other material having a high co-efficient of expansion and an inner tube or rod 9 of porcelain, carbon, nickel, steel, or "Invar" metal, the latter being secured at its upper end to the adjacent portion of the outer element 8 and terminating at its lower end in a knife edge 10 which bears against the thermostat lever 11. The short arm of this thermostat lever is supported on a second knife edge 12 secured to the casting which carries the thermostat chamber and the inclosed thermostatic element, and the long arm of said lever passes through a fork 13 secured to the upper end 110

of the vertical stem 14 of the gas valve 15. This gas valve 15 is hanging freely on the lower end of the stem 14 and is supported in position by an adjustable screw 16 passing 5 through the upper end of the fork 13, and bearing on the outer end of the thermostat lever 11. The latter is held in engagement with the knife edges 10 and 12 by means of the spring 17 which also serves to support 10 the valve parts in position. The check valve 3 engages on its lower side with a boss on the stem 18 which passes up through a stuffing box in the upper part of the chamber 2 and terminates just below the gas valve 15 15 in a collar 19. A compression spring 20 is interposed between the collar 19 and the lower wall of the gas valve chamber, and serves to keep both the check valve 3 and the gas valve 15 normally closed. Gas is admitted 20 to the upper portion of the gas valve chamber through the fuel supply pipe G and led away from the lower part of the chamber through a pipe I which is in communication with the main burners of the water 25 heater. A second small pipe 21 leads from the upper portion of this gas valve chamber to the ordinary pilot light which is used for igniting the gas supplied to the main burners through the pipe 22.

30 The operation of the above described mechanism is as follows: When there is no water or other liquid in the system, or when the liquid in said system is at rest the check valve 3 will be closed by the pressure of 35 the spring 20, and this spring will likewise hold the gas valve 15 tightly against its seat so that no fuel can pass to the main burners no matter what may be the position of the thermostat parts. When water begins 40 to flow through the system the check valve 3 will necessarily open and the downward movement of this valve will compress the spring 20 drawing the collar 19 away from the back of the gas valve 15 and leaving it subject only to the control of the thermostatically operated parts. If the liquid 45 in the thermostat chamber is below a certain temperature the thermostat lever 11 will be depressed far enough to allow the gas valve 50 15 to fall away from its seat under the action of gravity alone, and fuel will then flow from the upper part of the gas valve chamber into the lower part and thence through the pipe I to the main burners 55 where it is ignited by the flame of the pilot light which is constantly supplied with gas through the pipe 21. As the temperature in the thermostat chamber 7 rises the expansion of the outer positive thermostat 60 element 8 lifts the knife edge 10, and allows the thermostat lever 11 to be raised by the spring 17 thereby drawing the gas valve 15 against its seat and closing off the flow of fuel from the upper to the lower portion 65 of the gas valve chamber. When the gas

valve 15 is seated the motion of the thermostat lever 11 under the action of the spring 17 ceases, the only effect of the further expansion of the thermostat element 8 being to lift the knife edge 10 out of engagement with the thermostat lever. When the temperature of the liquid in the thermostat chamber falls again the knife edge 10 will once more depress the thermostat lever 11 allowing the suspended gas valve to again open, once more turning on the supply of fuel to the main burners, and the above described operations will be repeated as the temperature rises and falls as long as the liquid continues flowing through the heater; and, as will be readily seen the movements of the gas valve under such circumstances will be entirely under the control of the thermostatically actuated mechanism. The gas valve may be made to open 80 and close at any desired temperature by simply varying the adjustment of the single screw 16, and by making the gas valve 15 of large diameter, a full supply of gas can be turned on through the main burners 85 through an exceedingly small movement of the thermostatically controlled parts, and a very close regulation of temperature of the liquid in the thermostat chamber thereby attained. But as soon as the flow of 90 liquid stops, or immediately upon the withdrawal of all of the liquid from the system the check valve 3, together with its stem 18 and attached collar 19, will be lifted by the spring 20 closing the gas valve 15 and 95 preventing any further movement of the latter by the action of the thermostat parts until water has once more been turned on, and the flow of liquid once more established through the heating coils.

Construction of Fig. 4.—In the arrangement shown in this figure the control mechanism is placed at the top of the heater, the cold water from the main being led directly to the upper end of the heating coils 100 through a pipe 22. After passing through the heating receptacle the liquid emerges from the lower portion thereof, enters the lower end of the thermostat chamber 23, and passes upward through the same and 105 flows into the pipes 24 and 25 which supply the house system. The inlet passage 22 is in communication through a pipe 26 with the lower side of a diaphragm chamber 27; and the outlet pipe is similarly in communication through a passage way 28 with the upper portion of this diaphragm chamber. The diaphragm 29 which is between these two diaphragm chambers carries at its center a recessed metal cap 30 which 110 makes engagement with a loose stem 31 passing through a stuffing box in the wall of the upper diaphragm chamber. The gas valve chamber 32 in this construction is 115 formed in the same casting which carries 120

the thermostat chamber, and is made large enough to contain all of the thermostatic mechanism, so as to avoid as far as possible the use of stuffing boxes. The thermostat 5 is of the usual composite construction comprising an outer expansible tube 33 and an inner negative element 34 connected together at their lower ends; the upper end of the negative element 34 terminating in a knife edge 35 which engages with the thermostat lever 36. The latter is supported at its short arm end by an adjustable screw 37, and carries at its outer end a stud 38 and a lead weight 39. The end of the stud 10 38 bears against the upper surface of a gas valve 40 which rests loosely on its seat and is adapted to open upwardly to admit gas from the main fuel line G' to the line I' which leads to the main burners of the heater. Secured to the lower face of the 15 gas valve 40 is a recessed collar 43 and interposed between the flange of this collar and the lower wall of the gas valve chamber is a spring 44 of just sufficient tension to lift the gas valve 40 when the latter is freed 20 from engagement with other parts of the mechanism. In the recess of the collar 43 is located the head of a stem 45 which passes through the lower wall of the gas valve chamber and carries at its lower end a second flanged head 46, the upper end of which is provided with a leather washer to seal the opening through which the stem 45 passes when the latter is raised. The lower 25 flange of the head 46 is in engagement with the upper end of the stem 31 and interposed between this flange and the adjacent wall of the gas valve chamber is a strong spring 47, the tension of which is sufficient to overcome the tension of the spring 44 and thus 30 normally hold the gas valve 40 in its closed position against its seat.

The operation of the above described mechanism is as follows: When the system 45 is filled with liquid at rest the pressure on the two sides of the diaphragm 29 is the same, and the tension of the spring 47 will, as just described, hold the gas valve 40 closed and prevent any fuel flowing from 50 the supply line to the main burners of the heater. But whenever a faucet in the house supply system is opened and the water begins to flow through the heater from the inlet 22 to the outlet 24 the water pressures on the two sides of the diaphragm 29 will be 55 unbalanced by the resistance to the flow of the liquid through the heating coils and the diaphragm will be forced upward by the greater pressure of the liquid on the inlet 60 side, thus lifting the stems 31 and 45 against the pressure of the spring 47, and freeing the gas valve 40 from the restraining influence of this spring. If now the temperature of the water in the thermostat chamber 65 is less than that for which the thermo-

stat may be set the stud 38 will be held out of engagement with the back of the gas valve 40, and the latter will therefore be raised from its seat by the spring 44 thus allowing the fuel to flow through 70 the gas valve chamber to the main burners of the heater where it will be ignited by the flame of an ordinary pilot light supplied with gas through the auxiliary connection 50. As the temperature in the thermostat chamber 3 increases the expansion of the outer element 33 lowers the knife edge 35 and allows the stud 38 to be brought into engagement with the back of the gas valve 40, and the weight 39 will then 75 force this gas valve shut against the tension of the spring 44 thereby stopping the flow of fuel to the main burners. When the temperature in the thermostat chamber again falls the contraction of the element 33 lifts 80 the knife edge 35 and with it the thermostat lever 36 and weight 39, freeing the gas valve 40 from the closing pressure of the weight 39 and again allowing it to open under the tension of the spring 44. Whenever the 85 flow of water is stopped, or whenever the water is entirely withdrawn from the heating system the pressures on the two sides of the diaphragm 29 will be at once equalized, and the stem 45 will be depressed by the 90 spring 47 thus positively closing the gas valve 40 and holding it locked against its seat independently of any action of the other parts until water has once more been turned on and the flow of liquid once more 95 established between the inlet pipe 22 and the outlet pipe 24.

Construction of Fig. 5.—In the construction shown in this figure the cold water from the main passes through the pipe 51 105 into the upper end of a cylinder 52, and thence through the port 53 and the pipe 54 to the cold water inlet of the heating coils. The water actuated piston member 55 is secured to a stem 56 which passes through a 110 stuffing box in the upper wall of this water cylinder and terminates in a tapered forked shaped cam 57 which embraces the head 58 on the stem 59 of the gas valve 60. The tapered sides of this forked shaped cam 57 115 bear against pins 61 on the head 58, and the engagement between these parts acts to close the gas valve 60 when the piston 58 and the cam 57 are raised. A spring 62 placed behind the gas valve 60 serves to 120 keep said valve normally raised from its seat when its stem is out of engagement with the other actuating portions of the mechanism. The cold water after passing through the heating receptacle emerges 125 from the hot water outlet 63 and enters the thermostat chamber 64, which contains a thermostat of the same general construction as that shown in Figs. 3 and 4. The terminal knife edge 70 of this thermostat 130

engages with the short arm of the thermostat lever 71, and the long arm of said lever carries an adjustable screw 72, which terminates opposite the end of the head 58. 5 The thermostat parts are kept in operative engagement with each other by means of a strong tension spring 73. G² is the inlet to the gas valve and I² is the outlet therefrom. The operation of the control mechanism 10 just described is as follows: When no water is flowing through the heater the piston member 55 is raised to the position shown in dotted lines by the action of the spring 75, and in this raised position of the water 15 actuated piston member the gas valve 60 is kept closed against the pressure of the spring 62 by the engagement of the tapered cam shaped member 57 with pins 61. When a house service tap or other outlet in the 20 line supplied with hot water by the heater is opened the liquid is first withdrawn from behind the piston 55, and the resultant increase of pressure on the front of the piston depresses the latter against the pressure of 25 the spring 75 thus allowing the cold water to flow directly through the port 53 into the feed pipe 54. This depression of the piston member 55 withdraws the cam shaped member from engagement with the pins 61 30 and allows the gas valve 60 to open under the pressure of the spring 62, thus allowing fuel to flow through the gas valve chamber into the line I² which leads to the main burners of the heater. As the liquid rises 35 in temperature the thermostat by its expansion will lift the terminal knife edge 70 allowing the thermostat lever 71 to be moved to the right by the tension of the spring 73, and the continuance of this movement 40 brings the screw 72 into engagement with the head 58 and closes the gas valve 60 thus shutting off the supply of fuel to the main burners. When the temperature falls again the contraction of the thermostat depresses 45 the terminal knife edge 70, moves the thermostat lever 71 to the left, and freeing the head 58 from engagement with the thermostat lever screw 72, thus allowing the gas valve 10 to again open and again supply 50 fuel to the main burners. This intermittent opening and closing of the gas valve with variations in temperature in the heated liquid will continue as long as water flows through the heater. But as soon as the 55 water is shut off the piston member 55 will be raised by the spring 75, and if at this time the gas valve 60 is open it will be immediately closed by the action of the cam shaped member 57, and will be held closed 60 until a flow of water is once more started. It is also evident that the gas valve will be locked in its closed position whenever the heater is emptied of liquid so that no gas can possibly be turned on at such times.

65 *Construction of Fig. 6.*—In the modifica-

tion of the construction shown in Fig. 6 the arrangement of parts is precisely the same as that shown in Fig. 5, save that the thermostat lever 71 is moved slightly to the left. In this construction the cam shaped fork 57 70 is replaced by a flat plate 80 secured to the upper end of the stem 56 of the water actuated member, and the head 58 is replaced by a toggle joint system of levers 81 and 82 the ends of which are pivoted respectively 75 to a block 83 sliding on the stem 89 of the gas valve and to a standard 84 secured to the upper head of the water cylinder 82. The central part of the gas valve stem 89 has secured to it a collar 85 which is adapted to 80 make engagement with the block 83. The torsion springs 86 secured to the opposing arms on the toggle joint levers serve to keep these levers in their open position. The operation of this mechanism will be readily 85 understood. When the piston member and the head 80 are depressed as shown in Fig. 6 the opening of the toggle joint lever system draws the block 83 to the left out of engagement with the collar 85 and allows this 90 collar and the stem 89 of the gas valve to also move to the left thus opening the fuel valve and admitting gas to the main burners of the heater. When the water actuated piston member and the plate 80 are raised the 95 toggle joint lever system will be closed or shut up thus moving the block 83 to the right into engagement with the collar 85 and closing the gas valve against the pressure of the spring behind the gas valve. 100

105 *Construction of Fig. 7.*—This figure illustrates a very simple and compact arrangement of parts particularly adapted for use on small sized heaters. In this construction the entire control mechanism is placed at the hot water outlet of the heater. The water emerging from this outlet—which is indicated by the reference character 91—enters the thermostat chamber 92, and passes therefrom through a port 93 into the lower end 110 of a cylinder 94 and emerges through a pipe 95 leading to the house supply system. The water actuated member 96 is in this case a packed piston member and has ports 97, 97, which, in the lower position of the piston member 96, are closed by a self-adjusting plate valve 98. The stem 99 of the piston member 96 passes through a stuffing box in the upper head of the cylinder and terminates opposite a plate 100 on the lower end 115 of a stem 101. This stem enters the lower part of the gas valve chamber 102 and terminates in a head 103 which engages with a forked collar 104 secured to the lower side 120 of the gas valve 105. On the other side of said gas valve there is a second fork carrying an adjustable screw 106 which engages a notch in one end of the lever 107, and secured to the other end of this lever is a lead 125 weight 108 sufficiently heavy to overbalance. 130

the weight of the unrestrained gas valve 105. In the thermostat chamber 92 I place a liquid thermostat composed of two concentric corrugated tubes 109 and 110 hermetically sealed and filled with some liquid having a high coefficient of expansion such as ether, crude oil, or water, the choice of liquid being determined to some extent by the temperature at which it is desired to operate. The lower end of the thermostat tubes 109 and 110 are secured to the head 111 which closes the lower end of the thermostat box 92, and the upper ends carry a plate 112 which bears against the stem 113, and said stem passes through a stuffing box in the wall of the gas valve chamber and engages with the lower side of the lever 107.

The operation of the control mechanism just described is substantially the same as that of the preceding constructions and will be rendered clear by very brief description. When no water is flowing the pressures on the two sides of the piston member 96 will be equalized by a slight leakage of liquid 25 through the ports 97, 97 and the piston member will be held in its lowest position by the pressure of the spring 115, which likewise serves to hold the gas valve 105 in its closed position at such times through the 30 engagement of the head 12 with the forked collar 104. As long as no water flows therefrom, or whenever water is entirely withdrawn from the system, the gas valve 105 will remain shut preventing any passage of 35 fuel through the gas valve chamber 102. When a flow of water is started by opening an outlet in the pipe 95 the pressure on top of the piston 96 will be reduced, and said piston will be forced upward against the 40 pressure of the spring 115 simultaneously raising the stem 101 and releasing the gas valve 105 from the restraining influence of that spring. The gas valve 105 will then be raised by the counterweight 108 until the 45 arm 107 comes into contact with the thermostat stem 113. This raising of the gas valve to the extent permitted by the position of the stem 113 will allow more or less fuel to flow through the gas valve box from the sup- 50 ply pipe G³ to the feed pipe I³ which leads to the main burners. As water flowing through the thermostat chamber 92 rises in temperature the thermostat elements will expand, raising the stem 113 and with it the weight 55 108, allowing the gas valve 105 to fall until it is seated, thereby cutting off the fuel supply to the feed pipe I³. The gas valve 105 will be held closed by its own weight, and by the pressure of the fuel in the upper portion 60 of the valve box chamber until the thermostat elements have contracted sufficiently to withdraw the stem 113 from engagement with the arm 107, and then the fuel valve 105 will be once more opened and lifted by 65 the weight 108. As long as the flow of

liquid continues these intermittent movements of the gas valve will be controlled solely by the action of the thermostat parts; but as soon as the flow of liquid is stopped the immediate equalization of the water 70 pressure on the two sides of the piston member 96 will allow the spring 115 to depress said piston member and the stem 101, to the position shown in the figure, and this depression of the stem 101 brings the head 75 103 once more in engagement with the forked collar 104 thereby closing the gas valve 105, the tension of the spring 115 being sufficient to overcome the effect of the unbalanced component of weight 108. 80

Construction of Fig. 8.—This figure also illustrates a very simple and compact construction, in which the thermostat control element is of the same general character as that illustrated in Fig. 7. The hot water 85 after passing through the heater coil emerges from an outlet 121 and passes through the thermostat chamber 122 and enters the pipe 123 which communicates with the house supply system. The thermostat 90 element 123 is of the same construction, as already stated, as that illustrated in Fig. 7, save that the upper plate 125 is not perforated for the admission of water to the space within the inner corrugated tube, but 95 is made solid and bears at its center against the upper end of a hollow stem 136 which passes downward through the gas valve chamber 127 and the gas valve 128 and at its lower end is threaded to receive the nut 129 100 and a lock nut 130. Interposed between the upper end of the stem 126 and the bottom of the thermostat chamber is a stiff spring 131 which is normally under compression. The top of the thermostat chamber is closed by a flexible diaphragm 132 to the center of which is secured a stem 133 which projects both above and below the diaphragm. The upper end of this stem is threaded to receive a nut 134 which bears 110 upon the top of a compression spring 135 inclosed in a chamber formed by the cap 136. The space above the diaphragm communicates through a pipe 137 with a cold water feed pipe 138 115 which leads from the water main to the cold water inlet of the heater. The lower portion of the stem 133 passes through the stuffing box 139 in the end plate of the thermostat element, continues down through the 120 hollow stem 126, and is threaded at its lower end to receive a leather faced nut 140 which is adapted to engage with the end of a hollow cap 141 which is screwed to the back of the gas valve 128 and serves to 125 cover and inclose the parts 129, and 130 and prevent the passage of gas from one side to the other of the valve through the opening for the stem 126.

The operation of the mechanism shown 130

in Fig. 8 is as follows: When no water is flowing through the heater the pressures on the two sides of the diaphragm 132 will be substantially the same, and under such circumstances the compressive action of the spring 135 will lift the diaphragm and the stem 133 to the position indicated in dotted lines in Fig. 8 and this lifting of the stem 133 will force the gas valve 128 against its seat preventing all passage of fuel through the gas valve chamber. When the flow of cold water is started through the heater the pressure on the lower side of the diaphragm 12 will be reduced by the resistance 10 to the flow of the liquid through the heater coils, and the greater pressure of the water on the upper side of said diaphragm will depress it to the position shown in full lines in Fig. 8, thereby allowing the gas valve 15 to drop away from its seat and permit 20 the fuel to flow from the inlet passage G^4 to the outlet passage I^4 which communicates with the main burners of the heater. As the water in the thermostat chamber 122 25 becomes hotter the liquid in the thermostat element 124 expands, lifting the plate 125 and allowing the stem 126 to be raised by the spring 131 thus closing the gas valve 121 and shutting off the flow of fuel through 30 the gas valve chamber. The temperature at which the gas valve completely closes can be regulated by nuts 129 and 130, these being readily adjusted by the removal of the nut 140 and the cap 141. If the temperature 35 in the thermostat chamber should for any reason continue to rise after the gas valve 128 has closed the subsequent upward movement of the plate 125 will not be limited or restrained by the seating of the 40 valve 128 and the consequent cessation of movement of the valve parts. When the temperature in the thermostat chamber 122 falls the thermostat element 124 will shorten again under the pressure of the water in 45 the thermostat chamber, and the plate 125 will come into contact with the end of the stem 126 compressing the spring 131 and allowing the gas valve 128 to open again admitting more fuel to the main burners. 50 This controlling and regulating action of the thermostat in shutting off or supplying fuel to the main burners will continue as long as water continues to flow through the heater. But as soon as the flow of water 55 is stopped or whenever the water is entirely withdrawn from the system the equalization of pressure on the two sides of the diaphragm 132 will permit the spring 135 to raise the stem 133 thereby forcing the 60 gas valve 128 to its seat and holding it closed until a flow of water is once more set up through the heater coils.

Construction of Fig. 9.—This figure illustrates the application of my improvement 65 to a standard type of the so called "instant-

taneous" water heater in which the cold water flows from the main through a pipe 151 into the rear end of a water cylinder 152 containing a piston 153 which is held normally at the left hand end of the cylinder 70 by means of a compression spring 154. A port 155 leads from the upper part of the water cylinder 152 to a pipe 156 which communicates through the regulating cock 157 with the inlet 158 to the heating receptacle. After passing through this series of heating coils from the top to the bottom the water emerges from an outlet 159 and enters a vertical thermostat chamber 160 which communicates at the top with a pipe 80 161 leading to the house supply system. Located in the thermostat chamber 10 is a composite thermostat element, of a construction similar to that illustrated in Figs. 3 and 4, engaging at its lower end with an adjustable screw 162 in the thermostat lever 163. This thermostat lever 163 carries at the end of its long arm a second adjusting screw 164 engaging in turn with a second thermostat lever 165, the long arm of which bears 85 against a collar 166 at the outer end of a stem 167. This stem 167 passes through a stuffing box 168 in the front wall of the gas valve chamber 169 and terminates at its inner end in the gas valve 170 which separates the two parts of the gas valve chamber 90 169. A spring 171 is interposed between the front wall of the gas valve chamber and the end of the thermostat lever 165 and serves to keep the thermostat parts in operative engagement with each other. A second spring 172 of about half the strength of the spring 171 is interposed between the gas valve 170 and the adjacent left hand wall of the gas valve chamber. The stem 100 167 is made hollow to receive a second stem 173 which passes through a stuffing box 174 in the gas valve 170 and terminates in a head 175. A spring 176 of about the same strength as the spring 171 is interposed between the head 175 and the cap 177 at the right hand end of the gas valve chamber 169. This spring serves to normally hold the gas valve 170 in its closed position 110 against the lesser tension of the spring 172. The piston 153 in the water cylinder 152 bears against the inner end of a stem 178 which passes through a stuffing box 179 in the front wall of the water cylinder and terminates opposite the end of the stem 173. 115 At the front end of the water cylinder 152 there is a small port 180 which leads from the space in front of the piston 153 to the pipe 157.

The operation of the mechanism above 125 described is as follows:—When the system is filled with water at rest the piston 3 is held in the position shown in the figure by the tension of the spring 154. When a flow of water is started by opening a faucet in 130

the house pipe the pressure on the front side of the piston 153 is reduced by the withdrawal of cold water behind it, thus opening the port 155 and establishing free communication between the inlet pipe 151 and the cold water feed pipe 156. The forward movement of the piston 153 brings the end of the stem 178 into engagement with the end of the stem 173 and moves this stem and the attached collar 175 to the right compressing the spring 176 and relieving the gas valve 170 from the restraining action of this spring 176. Unless the temperature in the thermostat chamber 160 is too high the gas valve will now be opened by the action of the spring 172 allowing fuel to flow through the gas valve chamber 179 to the fuel feed pipe G⁵ which leads to the main burners in the base of the heater shell. The ignition of the gas at these main burners is accomplished by means of an ordinary pilot light which may be supplied with fuel through the independent connection 182. As the flowing water is heated and the temperature in the thermostat chamber 160 increases, the expansion of the outer element lifts the inner negative element allowing the thermostat lever system to be moved to the left by the pressure of the spring 171. This movement continues until the long end of the thermostat lever 165 comes in contact with the collar 166 on the gas valve stem 167 and forces the gas valve 170 shut, thus cutting off the supply of fuel to the main burners. When the temperature of the liquid in the thermostat chamber 160 falls, the thermostat lever system will be moved to the right by the contraction of the outer thermostat element compressing the spring 171 and leaving the gas valve 170 free to open again under the tension of the spring 172. This opening and closing movement will be continued as the temperature rises and falls until the flow of water through the heater is stopped. As soon as this occurs the equalization of pressure on the two sides of the piston 153 allows the latter to be moved to the left by the action of the spring 154 thus withdrawing the stem 178 from engagement with the stem 173 and bringing the collar 175 once more into contact with the gas valve 170, which will then be forced shut by the pressure of the spring 176, and held locked in its cut-off position—no matter what may be the movements of the thermostat mechanism—until the latter once more begins to flow through the heater coils.

Construction of Fig. 10.—Fig. 10 illustrates a slight modification of the construction shown in Fig. 9. In the arrangement illustrated in Fig. 10, the stem 183 terminates at its outer end in a head 184 which is adapted to engage with a fork 185 secured to the outer end of the gas valve stem

186. When the water is at rest the piston 153 is forced back by the spring 190. The stem 183 is held to the right by the spring 191 bearing against the head 192, and the head 184 engaging with the forks of the collar 185 pulls the gas valve 187 against its seat and prevents any fuel flowing through the gas valve chamber. When the flow of water is started the piston 189 is moved to the right finally engaging the head 192 and securing the release of the head 184 from engagement with the forks of the collar 185, and freeing the gas valve from the locking action of the spring 191, thus allowing it to open under the action of the spring 188. As the temperature of the flowing water rises and falls, the position of the gas valve 187 is correspondingly altered as before by the movement of the thermostat lever 165 which engages with the flanged end of the forked collar 184. The lost motion connection between the piston 189 and the stem 183 permits the slight amount of movement of the piston due to reactions in the heater to occur without opening the gas valve.

It will be noted in all of the modifications of the structure as heretofore described, that the fluid actuated member and fuel valve are so connected that when no water is flowing, or when the liquid is entirely withdrawn from the heating system, the fuel valve will be held closed and cannot be moved by any action of the thermostat no matter what position the thermostat parts may assume. It will be further noted that the said connections between the water actuated member and the fuel valve provide for the complete release of the latter from any restraint by the former when the fluid actuated member is moved by the flow of liquid through the heater, thus leaving the fuel valve at such times solely under the control of the thermostat and its connected control mechanism. The latter mechanism is so arranged that it has no direct effect on the opening movements of the fuel valve, these movements being effected solely by means which act independently of both the water control mechanism and the temperature control mechanism. The thermostat parts moreover do not act directly on the valve in closing the latter but act simply to control the movements of a spring or weight which in turn closes the fuel valve when the thermostat permits of this. In consequence of these characteristics of operation the fuel valve of my improved double control mechanism may be said to be normally open in the sense that it is opened whenever it is freed from the restraining influence of the water actuated control mechanism and temperature actuated control mechanism. The closing of the valve is effected by the action of parts which may exert any desired degree of force and which therefore are not affected in

their operation by the restraining influence of the parts which open the valve. These parts which close the valve act upon it moreover only at the instant of closing. At other times they act upon and are controlled by the thermostat lever system alone. It results from this that the thermostat parts are not restrained in their action by any fixed points of movement in the valve path, and after said valve has closed the thermostat parts may go on moving without throwing any strain upon any part of the temperature control mechanism. The same statement is true of the movement of the thermostat parts in the opposite direction, that is the direction taken when the temperature is falling and the valve is being released from the action of the spring or weight which has closed it. Both the opening and the closing movements of said valve are therefore rendered quick and positive and all delicate balances of opposing springs and the consequent uncertainty and hesitation of movement of the valve parts controlled thereby are thus avoided.

It is obvious—as shown by the various illustrations above presented—that my improvements are capable of embodiment in various detail forms; and that numerous modifications of the mechanical construction may be made without departing from my invention.

Having thus described my invention and illustrated its use, what I claim as new and desire to secure by Letters Patent is the following:

1. In combination in an instantaneous water heater, a water actuated means operated by opening and closing the outlet from the heater, a thermostat, a gas valve yieldingly maintained in open position when not acted upon externally, means controlled by the said water actuated means for maintaining the gas valve yieldingly in closed position when the outlet from the heater is closed and permitting the gas valve to open when the said outlet is open and the temperature of the water is below a predetermined point, and yielding means controlled by the thermostat for closing the gas valve when the temperature of the water rises above said predetermined point.

2. In combination in an instantaneous water heater, a water actuated means operated by opening and closing the outlet from the heater, a thermostat, a gas valve yieldingly maintained in open position when not acted upon externally, means controlled by the said water actuated means for maintaining the gas valve yieldingly in closed position when the outlet from the heater is closed and permitting the gas valve to open when the said outlet is open and the temperature of the water is below a predetermined point, and means whereby the valve

is permitted to close yieldingly when the temperature of the water rises above said predetermined point, the said yielding closure being under the control of the thermostat.

3. In combination in an instantaneous water heater, a water actuated means operated by opening and closing the outlet from the heater, a thermostat, a gas valve yieldingly maintained in open position when not acted upon by the thermostat or the water actuated means, means controlled by the said water actuated means for maintaining the gas valve yieldingly in closed position when the outlet from the heater is closed and permitting the gas valve to open when the said outlet is open and the temperature of the water is below a predetermined point, and means whereby a yielding closure of the gas valve is secured when the temperature of the water rises above said predetermined point, the said yielding closure being under the control of the thermostat.

4. In combination in an instantaneous water heater, a water actuated means operated by opening and closing the outlet from the heater, a thermostat, a gas valve yieldingly maintained in open position when not acted upon by the thermostat or the water actuated means, means controlled by the said water actuated means for maintaining the gas valve yieldingly in closed position when the outlet from the heater is closed and permitting the gas valve to open when the said outlet is open and the temperature of the water is below a predetermined point, and yielding means controlled by the thermostat for moving the gas valve to closed position when the water rises above said predetermined point.

5. In combination in an instantaneous water heater, a water actuated means operated by opening and closing the outlet from the heater, a thermostat, a gas valve yieldingly maintained in open position when not acted upon by the thermostat or the water actuated means, means controlled by the said water actuated means for maintaining the gas valve yieldingly in closed position when the outlet from the heater is closed and permitting the gas valve to open when the said outlet is open and the temperature of the water is below a predetermined point, and a spring, held normally in inoperative position by the thermostat, but permitted thereby to operate and close the gas valve when the temperature of the water rises above a predetermined point.

6. In combination in an instantaneous water heater having an inlet and an outlet, a reciprocating water actuated element operated by opening and closing the outlet from the heater, a thermostat, a gas valve, a spring tending to open the gas valve, a second stronger spring tending to close the gas

valve when the outlet from the heater is closed and the water actuated element is in its rear position, but restrained from acting on the valve to close it when the outlet from 5 the heater is open and the water actuated element is in its forward position, and a third spring also stronger than the first spring and controlled by the thermostat for closing the gas valve when the temperature 10 of the water in the heater rises above a predetermined point.

7. In combination in an instantaneous water heater having an inlet and an outlet, a reciprocatory water actuated means operated by opening and closing the outlet from 15 the heater; a thermostat, a gas valve, a tubular stem therefor controlled from the thermostat, a spring for moving the tubular stem to close the valve when the temperature 20 of the water in the heater rises above a predetermined point, a second spring weaker than the first spring for opening the valve

when the first spring is restrained by the thermostat from acting upon the tubular stem, a rod extending slidably through the 25 tubular stem and provided with means for engaging the valve and closing it when the rod is in its forward extreme of movement, and a third spring stronger than the second spring for moving the rod to such forward 30 extreme of movement, the said water actuated means and the rod being positioned so that the rod is moved to restrain the third spring and permit the valve to open under the influence of the second spring when the 35 outlet from the heater is opened.

In testimony whereof I have hereunto signed my name in the presence of the two subscribed witnesses.

FRANK L. O. WADSWORTH.
